[57] **CLAIM**

The ornamental design for a portable seat or similar article, as shown and described.

DESCRIPTION

FIG. 1 is a top plan view of a portable seat or similar article showing our design in its folded condition; FIG. 2 is a bottom plan view of the design of the present invention shown in FIG. 1;

FIG. 3 is a side elevational view of the design according to the present invention shown in unfolded condition, this view representing a mirror image of the side elevational view of its opposite side;

FIG. 4 is a front elevational view of the design shown in FIG. 3;

FIG. 5 is a rear elevational view of the design shown in FIG. 3;

FIG. 6 is a perspective-type view of the design shown in FIG. 3; and

FIG. 7 is a side elevational view of the design shown in FIG. 1 in its folded condition, this view being a mirror image of the opposite side elevation.
